(57) **CLAIM**

The ornamental design for a control unit, as shown and described.

DESCRIPTION

FIG. 1 is a top perspective view of the control unit;
FIG. 2 is a top view of the control unit, taken from the frame
of reference of FIG. 1;
FIG. 3 is a bottom view of the control unit, taken from the
frame of reference of FIG. 1;
FIG. 4 is a side view, in elevation, of the right side of the
control unit, taken from the frame of reference of FIG. 1;
FIG. 5 is a side view, in elevation, of the left side of the
control unit, taken from the frame of reference of FIG. 1;
FIG. 6 is a front view of the control unit, taken from the
frame of reference of FIG. 1;
FIG. 7 is a rear view of the control unit, taken from the frame
of reference of FIG. 1; and,
FIG. 8 is a bottom perspective view of the control unit.
The broken lines are included for the purpose of illustrating
unclaimed portions of the control unit and form no part of
the claimed design.
